Patented Apr. 23, 1889.

UNITED STATES PATENT OFFICE.

FRED H. KINDL, OF CHICAGO, ILLINOIS.

MACHINE FOR SHAPING METAL STRIPS FOR ORNAMENTAL METAL LATTICE OR FENCE WORK.

SPECIFICATION forming part of Letters Patent No. 402,087, dated April 23, 1889.

Application filed September 5, 1888. Serial No. 284,655. (No model.)

To all whom it may concern:

Be it known that I, FRED H. KINDL, a citizen of the United States, residing at Chicago, in the county of Cook and State of Illinois, 5 have invented a certain new and useful Improvement in Machines for Shaping Metal Strips for Ornamental Metal Lattice-Work, of which the following is a specification.

My invention relates to the production of 10 metal strips adapted for forming ornamental lattice-work and involving at intervals along each strip certain half-twists which are alternately made in reverse directions, whereby the flat-strip portions between the points of 15 twist may alternately lie in different planes.

The objects of my invention are to avoid 20 the slow, expensive, and laborious process of hand-twisting and the liability of tearing the metal at the points of twist, and to produce said strips in a rapid, economical, and generally efficient way.

In the drawings, Figure 1 represents in 25 side elevation a machine comprising in its structure a pair of rolling-dies adapted for rolling out the strips in accordance with my invention and further involving a pair of 30 punching dies or rolls. Fig. 2 represents a section taken through Fig. 1 on the line 2 2. Fig. 3 represents a section taken through portions 35 of the rolls A and A' on a plane at right angles to their axis of rotation. Fig. 4 is a like view of two punching-rolls. Fig. 5 represents a section on line 5 5, Fig. 3. Fig. 6 represents a section on line 6 6, Fig. 3. Fig. 7 represents a section on line 7 7, Fig. 4. Fig. 40 8 represents in perspective a portion of one of the reversely-twisted strips. Fig. 9 represents a portion of one of said reversely-twisted strips on a somewhat larger scale. Fig. 10 represents in perspective a portion of 45 the roll A. Fig. 11 is a face view of the portion of the roll shown in Fig. 10. Fig. 12 is a section through Fig. 10 on the line 12 12. Fig. 13 represents a section taken through a 50 portion of a roll provided with a die-face and a side elevation of a die-block provided with a corresponding die-face, the section through the roll being understood to be on a plane transversely to the axis of the roll. Figs. 14 and 15 represent portions of lattice-work 55 formed by the reversely-twisted metal strips.

The rotary heads or rolls A and A' are pro-

vided with dies for rolling flat metal strips into the form herein illustrated by the strip B, which is understood to have been shaped 55 by the conjoint action of the rolling-dies. This said strip is at intervals along its length bent to provide it with a series of half-twists, which are made alternately in reverse or opposite directions, the twists b in the strip being the reverse of the twists b', with which they alternate. The foregoing arrangement of reverse twists serves to bring the intervening flat portion of the strip alternately in different planes. 60

In the specimen strip herein shown the flat portions b², which alternate with the flat portions b³, are arranged in a plane which is at right angles to the plane in which the flat portions b³ are arranged. Strips thus 70 shaped may be riveted together to form ornamental lattice-work, such as shown in Figs. 14 and 15, wherein the strips are riveted together at their flat portions b², which may occupy vertical planes, while the flat portions b³, which are intermediate of such riveted 75 portions, may lie in horizontal planes.

As a construction of dies for rolling flat metal strips into the shape hereinbefore set forth, each roll is provided with a peripherally-arranged die-face comprising a series of flat-face portions, a, arranged in a plane that is perpendicular to the axis of the roll, and a series of flat-face portions, a', which are formed on planes at right angles to the 85 plane of the said die-face portions a, in which way the die-face portions a correspond, for example, to the flat-strip portions b³, while the die-face portions a' correspond to the flat-strip portions b² of the finished strip. The 90 die-face portions a are on a plane which intersects the die-face portions a' midway of their width, while, on the other hand, each die-face portion a' is on a plane which intersects the two next adjacent die-face portions a midway 95 of the width of the latter. At the points of junction between said flat die-face portions a and a' the die-face is provided with curved-face portions, which are curved alternately in reverse directions and shaped in correspondence to the twists that are to be rolled in the metal strips, the curved die-face portions a² being, for instance, shaped in conformity to the twists b of the complete strip, in which 100

case the reversely-curved die-face portions a^3 are shaped in conformity to the reversely-formed twists b' .

While the rolling-dies herein illustrated are arranged with their flat-face portions a in a plane perpendicular to the axes of the rolls, and their flat die-face portions a' in planes that are at right angles to the plane of said die-face portions a , as best illustrated by Figs. 5 and 6, it is not strictly necessary that said die-face portions should be arranged at such precise angles relatively to the axes of the rolls, since, for example, the die-faces can be arranged obliquely to the axes of the rolls without destroying the desired arrangement of the die-face portions a and a' relatively to each other.

By the foregoing arrangement flat metal strips fed in any suitable way to the rolling-dies may be rolled into the ultimately required reversely-twisted form.

In order to accurately guide the strips and hold them properly subject to the action of the dies, each roll is preferably provided with an annular flange which is desirably received within a correspondingly-shaped annular groove in the opposing roll, as best shown in Figs. 5 and 6, wherein the roll A' is provided with a peripheral groove adapted to receive a flange, a^4 , of the roll A , while the roll A is in like manner provided with a peripheral groove adapted to receive a flange, a^5 , of the roll A' . These flanges may be either made integral with the rolls or may be formed by circular plates made somewhat larger in diameter than the diameters of the rolls and bolted or otherwise suitably secured to the same. The flanges serve, as aforesaid, to guide the strips while the latter are passing between the dies of the two rolls, while by extending the flange of each roll into an annular recess of the opposing roll the two rolls are so interlocked as to co-operate in resisting any tendency on the part of the work to cause an end-thrust of either roll during the operation of rolling the twists in the metal strips.

In Figs. 1 and 2 the rolls A and A' are journaled in a suitable frame and geared together by means of gears D and D' as a simple means for insuring the synchronous rotation of the rolls and causing the die-face portions of one roll to match the corresponding die-face portions of the other roll. It is, however, understood that any suitable means for insuring the proper relative rotation of rolling-dies may be employed in connection with the said rolls.

In connection with the rolls A and A' , I propose in practice to provide some convenient arrangement of stop device—such, for example, as an ordinary clutch used for stopping and starting machinery—whereby the action of the dies upon the strip may be arrested at any desired point along the same, it being obvious that various devices for either automatically cutting off the transmission of power to the rolls or for permitting such arrestment to be performed by manual labor

can be provided. A stoppage of the machine (or the rolls, which may be comprehended under such term) will permit strips B to be produced with a suitable length of unbent portion, b^4 , Fig. 10, at either or both ends, so that, where desired, said ends may be subsequently bent to form scrolls or the like.

The foregoing explanation of the desirability of stopping the rolls at certain times is herein made as explanatory of the feature herein shown of journaling the axle E of the roll A eccentrically in rotary adjustable bearings e , which can be adjusted so as to lift the roll A from the roll A' , whereby the strip can be freely shifted along between or withdrawn from the dies, which at such period will be suitably separated for such purpose.

As a means for connecting the rotary adjustable bearings together, they may be provided with levers e' , connected together by any suitable connection—such, for example, as a rod, e^2 —whereby the adjustment of the bearings may be made synchronous. One of said levers is herein provided with a handle, and may be locked in any way suitable for locking a vibratory lever—as, for instance, the lever can be locked at a proper point along a slotted segment, e^3 , by a set-screw, or bolt and nut, or other like device, whereby, when said lever is properly locked, the roll A can be held down to its work.

F and F' are punching-rolls having face portions corresponding to the die-face of the rolls A and A' . One of the rolls F and F' (for example, the roll F) is provided with a series of punches, f , while its companion roll is provided with recesses f' , which are to register with the punches. By such arrangement a strip, B , can pass from the rolling-dies of rolls A and A' to the punching-rolls, between which latter the rivet-holes b^5 can be punched in the strip. The rolls F and F' may be geared together and also may be gear-connected with either or both of the rolls A and A' . The roll F can also have its axle f^2 journaled eccentrically in rotary adjustable bearings f^3 , (one of which is shown in Fig. 1,) corresponding to the rotary adjustable bearings, in which the roll A is eccentrically mounted and for a like purpose. It is also understood that the rotary adjustable bearings for the roll F may be provided with connected levers, and that one of said levers f^4 can be locked to a segment, f^5 , or like device, so as to hold the roll F down when so desired.

While I prefer to arrange the rolling-dies upon a pair of holders consisting of rolls, and consider such arrangement the best, it will be seen by Fig. 13 that the strip could be formed by a rolling-die arranged upon a roll or rotary holder and acting in conjunction with a sliding die arranged upon a straight reciprocating block or holder. In said figure the roll A^2 is understood to be provided with a die-face similar to that of either the die or roll A or the die or roll A' , and that the sliding die-block A^3 is provided with a corre-

sponding die-face. The roll A could in such case be rotated so as to roll both ways, or it could be rotated continuously in one direction and the die-block reciprocated.

5. What I claim as my invention is—

1. As a means for rolling flat metal strips into the hereinbefore-described reversely-twisted strips having two portions which are intermediate of the twists alternately in different planes, a pair of dies, each having a series of substantially flat die-face portions alternately in different planes in correspondence with said portions of the strips that are intermediate of the twists, and a series of curved-face portions intervening between said flat die-face portions and alternately curved in reverse directions in correspondence with and to form the reverse twists in the strips, substantially as set forth.
- 20 2. In a machine for forming the within-described reversely-twisted metal strips, a pair of opposing rotary dies, each having die-face portions a , alternating with die-face portions a' , and reversely-curved face portions a^2 and a^3 , alternating with one another and formed at the points of junction between the die-faces a and a' , substantially as described.
- 25 3. In a machine for forming the within-described reversely-twisted metal strips, the flanged dies, each provided with a die-face comprising the portions a , a' , a^2 , and a^3 , for the purpose described.

4. In a machine for forming the within-described reversely-twisted metal strips, a pair of dies, each provided with a die-face comprising the alternately-arranged flat and curved portions, as set forth, for forming the reversely-twisted strips B, one of said die-holders being provided with a flange which works within a groove in the opposing die-holder, for the purpose described. 35

5. The combination, with the rolls provided with dies, each having the herein-described alternately-arranged flat and curved die-face portions for forming the reversely-twisted strips B, of a punching device arranged for punching rivet-holes in said strip, for the purpose described. 40

6. In a machine for forming strips B, the roll A, provided with the within-described die-face having the alternately-arranged flat and curved die-face portions, forming a die-face which is shaped in conformity to said strip, said roll being journaled eccentrically in rotary adjustable bearings, in combination with a separate movable die having alternately-arranged flat and curved die-face portions corresponding to and matching the said die-face portions of the die on roll A, substantially as and for the purpose described. 50
